INFANT'S FEEDING DEVICE

Stephen Baracate, Troy, N. Y.

Application July 19, 1950, Serial No. 174,682

8 Claims. (Cl. 215—11)

1

This invention relates to improvements in infants' nursing devices, having particular reference to a device which is valve-controlled, and the provision of such an article as well as the combination therewith of a nursing bottle and nipple is a principal object of the invention.

Generally it is an object of the invention to provide such a device which is economic of manufacture, simple yet sturdy and durable of construction, positive in operation and otherwise well suited to the purposes for which it is intended.

More specifically, it is an object of the invention to provide such a device having valve means with an inlet and an outlet providing communication between a nursing bottle and a nipple, and gravity-actuated means cooperating with the valve means for maintaining the inlet of said valve when submerged in a liquid food to provide positive communication thereof through said nipple.

Yet more specifically, it is an object of the invention to provide such a device having valve means with an inlet and an outlet providing communication between a nursing bottle and a nipple, a housing connecting the bottle and nipple, providing a chamber to hold a portion of liquid food flowing from the bottle, and for housing the valve means therein, and gravity-actuated means cooperating with the valve means for maintaining the inlet of the valve submerged in the food within the chamber.

Another object of the invention is to provide such a device having bearings in which such valve means may revolve freely about an axis extending in a direction longitudinally of the nipple.

Another object of the invention is the provision of bearings providing substantially free universal movements of such a valve means relative to the bottle and the nipple and gravity-actuated means such as, for example, a weight connected to the valve means to maintain the inlet submerged in the liquid during such times as the food is being sucked through the nipple.

Another object of the invention is the provision of such a device having bearings in which the valve means may revolve freely about an axis extending in a direction longitudinally of a nipple connected thereto, and bearings in which the valve means may revolve freely about an axis at right angles to the first mentioned axis.

A further object of the invention is the provision of such a device having valve means encased within a housing and providing communication between a bottle and a nipple adapted to be connected thereto and having an air inlet valve or passage in a wall thereof to prevent the creation of a vacuum and subsequent collapse

2

of the nipple during use, especially where a soft or conventional type of rubber nipple is used. It should be strictly understood however, that such a valve means is not absolutely essential, particularly where the nipple is made of a plastic substance, such as, for example, a thermoplastic or thermosetting material particularly designed for such a device as that embodied by the present invention. Furthermore, the invention primarily contemplates the use of such devices with plastic types of nipples as well as plastic types of bottles.

Other objects of the invention will in part be obvious and will in part appear hereinafter.

15 The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had to the following detailed description taken in connection with the accompanying drawing, in

25 which:

Fig. 1 is a plan view of the device having a nipple attached thereto at one end and connected at its other end to a bottle, the latter illustrating a fragmentary portion of the neck thereof only;

Fig. 2 is a transverse longitudinal sectional view of a device such as that depicted in Fig. 1;

Fig. 3 is an end elevational view, looking from left to right, of Fig. 2;

35 Fig. 4 is a partial transverse vertical sectional view of the device shown in Figs. 1 and 2;

Fig. 5 is a transverse sectional view taken along the line 5—5 of Fig. 4 and looking in the direction of the arrows;

40 Fig. 6 is a modification of a valve means, partly broken away and in section, embodied by the invention;

Fig. 7 is a transverse sectional view taken along the lines 7—7 of Fig. 6 and looking in the direction of the arrows;

45 Fig. 8 is a transverse sectional view taken along the lines 8—8 of Fig. 6 and looking in the direction of the arrows;

Fig. 9 is a side elevational view of a further

50 modification of a valve means embodied by the invention;

Fig. 10 is a transverse sectional view, taken along the lines 10—10, of Fig. 9 and looking in the direction of the arrows;

55 Fig. 11 is a side view of a fragmentary portion of a valve element applicable for use in connection with Figs. 1 through 5 and Fig. 6; and

Fig. 12 is a transverse sectional view, taken along the lines 12-12 of Fig. 11, and looking in the direction of the arrows.

It is well-known that conventional types of infants' feeding bottles cause what is commonly known as infants' colic and this is largely caused by improper flow of milk through the nipple because the same is not positively controlled, because there is an interruption of the flow thereof causing air to be drawn from the bottle through the nipple, and further because there is no proper means for supplying air to the bottle or zone from which the milk is withdrawn. Consequently, because of the air sucked through the nipple, and also because a vacuum is thus created, the walls of the nipple tend to collapse resulting in further sucking of air from the atmosphere adjacent the collapsed walls of the nipple. It has long been recognized that it would be a distinct improvement to overcome such difficulties or disadvantages and this is accomplished by means of the present invention.

Referring now more particularly to the drawing, there is illustrated generally at 20 an infant nursing device to be attached at one end to the neck of a nursing bottle 21 and to carry at its other end a nipple 22.

The device preferably comprises a housing, such as a cylindrical shell 23, which is internally threaded at its outer end to receive an end portion or wall 24 which is correspondingly threaded externally to be secured in the threaded shell 23. The wall 24 has a neck extension 25 suitably grooved to receive and hold the annular bead 26 of the nipple 22.

At its other end the shell may be suitably threaded internally, as at 27, to engage the neck of the nursing bottle in the event the latter is externally threaded with a standard size thread. It will be understood that the device preferably is made of plastic or suitable rubber material although any other material suitable for the purpose may be utilized.

Also, a suitable distance within the cylindrical shell 23, the same is internally threaded to receive an externally threaded partition 28 having a plurality of holes or apertures 29 therethrough, the partition being held in spaced relation from the end wall or portion 24 to provide a chamber 30 for the reception of a portion of the milk from the bottle when the same is tilted to permit the milk to flow therein through the holes 29.

Within the housing will be found valve means indicated generally at 31. Preferably, the valve means, also partly or wholly made from plastic material, constitutes a rectangularly shaped frame comprising spaced members 32 and 33 disposed longitudinally within the casing and being connected by transverse end members 34 and 35.

Extending from the rear transverse member is a trunnion or bearing 36 journaled in a bearing recess in the partition 28. At its other end a transverse member 35 is provided with a forwardly extending trunnion or bearing 37 journaled in the front or other end wall 27. This latter bearing member may extend partly or wholly through the end wall and through the neck 25. This type of arrangement permits rotation of the frame member and remaining portion of the valve means, about to be described, to rotate around a longitudinal axis.

Mounted transversely of the frame members 32 and 33 and journaled to rotate therein in suitable recesses provided therefor, is a tubular element 38 having a boss 39 at one end and a screw mem-

ber 40 at its other end to hold the same in rotatable position. At one end of the member 38, the same has an annular groove 41 with a hole 42 drilled therein to provide communication therewith (see Fig. 11). The tubular member 38 also is formed by virtue of a hole 43 drilled longitudinally thereof. Communication is thus far provided to the nipple by means of the hole 43, the hole 42, the annular groove 41, and a channel 45 extending through the member 32, the member 35, and the trunnion or bearing 37 to communicate with a hole or channel 46 extending centrally of the neck 25 of the end wall 24 and consequently to provide communication with the nipple 22.

Downwardly depending from the transverse tubular member 38 is a short tubular nipple 47. Secured to this nipple is a weight 48, preferably made of a metal which will resist corrosion due to lactic acid in the milk. This weight has an opening 49 therein and is flared outwardly within the internal bore of the weight to provide a recess for the reception of a valve closure and opening member such as a small metallic wall 50 which is slightly larger in diameter than the opening 49. Thus there is provided a valve means having an inlet 49 and an outlet 45 and 46 providing communication between the nursing bottle and the nipple 22. Because of the weight 48, the valve inlet 49 provides gravity-actuating means cooperating with the valve mean for maintaining the inlet thereof in a zone below the longitudinal axis of the device and submerged within the milk during the time the latter is being sucked through the nipple. In other words, there is provided a valve means with substantially free universal movement thereof relative to the bottle and the nipple so that the valve means may revolve freely about an axis extending in a direction longitudinally of the nipple and freely about an axis at right angles to the first axis.

The modification shown in Figs. 6-8 shows a somewhat similar type of rectangular frame arrangement having oppositely disposed members 51 and 52 adapted rotatably to receive within the opening 53 a transverse tubular member 38 connecting short nipple 47, and weight 48 such as that described above. The members 51 and 52 are connected at their rearward ends by transverse member 54 having a trunnion or bearing 55 as above described. However, the opposite end of the members 51 and 52 are connected by a cylindrical portion 56 adapted to rotate in an outer wall portion 57 similar in construction to the outer wall portion 22 above described. The outer end of the cylindrical portion 56 has an annular recess 58 which is in communication with a channel or passage 59 drilled through the member 51. The channel or recess 58 is also in communication with the nipple by means of the channel or hole 60 drilled through the outer wall or portion 57. The operation of a device embodied by this modification of the invention is similar to that described above in connection with the preferred form of the invention.

In Fig. 9, there is illustrated a further modification of the invention to be used in a housing such as that described in connection with Figs. 1 through 4. However, instead of a rectangular frame, there is substituted a cylindrical member 61 adapted to be journaled in the outer wall portion 24 at one end of the device and the partition 25 at the other end of the device. This cylindrical member is drilled with a longitudinal hole 62 to form a partial tube and outlet at one end which

communicates with an inlet by means of a short nipple 63 having a weight 64 connected thereto with a valve inlet (not shown) as above illustrated in Fig. 4. It will be understood that this modification is rotatable around the longitudinal axis, only.

It should also be understood that while the transverse element heretofore described (Fig. 2) thus communicates through only the member 32 and partially through 35, communication can likewise be effected by similarly drilling holes through the member 33 and completely through the remaining member 35 so that they are in communication with each other and so that a double channel may be provided as well as the single channels above described.

In order to prevent the creation of a vacuum within the device or within the bottle as hereinbefore referred to, it is desirable to provide an air inlet valve open to the atmosphere. Preferably, this is done by providing a threaded boss 65 on the casing or housing 23 and drilling a hole 66 therethrough adapted to receive a spring 67 and the ball valve element 68, the same being held in place by a cap 69 threadingly engaging the boss 65. The cap 68 is also provided with an opening 70 in coaxial alignment with the opening 66.

In order to provide the channels 45 in the frame members 32 and 35, respectively, holes may be drilled therein and subsequently plugged up as indicated at 71 and 72 (Fig. 2).

It will thus be seen that the objects hereinbefore set forth may readily and efficiently be attained, and since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention what I claim as new and desire to secure by Letters Patent is:

1. An infant nursing device adapted to be attached to a nursing bottle and to have a nipple attached thereto, comprising a housing, valve means rotatably mounted within said housing, said valve means having an inlet and an outlet adapted to provide communication between said bottle and said nipple, and gravity actuated means cooperating with said valve means to rotate the same around axes that are both longitudinal and transverse of said housing, and to maintain the inlet of said valve submerged in food when the same is carried within said housing.

2. In an infant nursing device the improvement comprising the combination of a casing adapted to be applied at one end to a nursing bottle containing a liquid food; of a noncollapsible nipple at the other end of said casing; valve means wholly secured within the confines of said casing, having an inlet and an outlet, providing communication between said bottle and said nipple; and gravity actuated means cooperating with said valve means for maintaining the inlet of said valve submerged in said food.

3. In an infant nursing device the improve-

ment comprising the combination of a casing adapted to be applied at one end to a nursing bottle containing a liquid food; of a nipple at the other end of said casing; valve means secured within the confines of said casing, having an inlet and an outlet, providing communication between said bottle and said nipple; bearings within said casing in which said valve means may revolve freely about an axis extending in a direction longitudinally of said nipple; and gravity actuated means cooperating with said valve means for maintaining the inlet of said valve means in a zone below said axis and in a substantially perpendicular position as the longitudinal axis of said bottle is rotated through a horizontal plane during the time said food is being sucked through said nipple; whereby to maintain the inlet of said valve means submerged in said food during said time.

4. In an infant nursing device the improvement comprising the combination of a casing adapted to be applied at one end to a nursing bottle containing a liquid food; of a nipple at the other end of said casing; a valve means wholly disposed within the confines of said casing and having an inlet and an outlet, providing communication between said bottle and said nipple; bearings within said casing providing substantially free universal movements of said valve means relative to said bottle and said nipple; and a weight connected to said valve means to maintain said inlet submerged in said food during such times as said food is being sucked through said nipple.

5. In an infant nursing device the improvement comprising the combination of a casing adapted to be secured at one end to a nursing bottle containing a liquid food; of a nipple at the other end of said casing; valve means wholly mounted within the confines of said casing and having an inlet and an outlet, providing communication between said bottle and said nipple; bearings within said casing in which said valve means may revolve freely about an axis extending in a direction longitudinally of said nipple; bearings within said casing in which said valve means may revolve freely about an axis at right angles to the first mentioned axis; and a weight cooperating with said valve means to maintain said inlet submerged in said food during such times as said food is being sucked through said nipple.

6. In an infant nursing device the improvement comprising the combination of a casing adapted to be secured at one end to a nursing bottle containing a liquid food; of a nipple at the other end of said casing; valve means wholly mounted within the confines of said casing, having an inlet and an outlet, providing communication between said bottle and said nipple; bearings within said casing in which said valve means may revolve freely about an axis extending in a direction transversely of the axis of said nipple; and gravity actuated means cooperating with said valve means for maintaining the inlet of said valve means in a zone below said transverse axis and in a substantially perpendicular position as the longitudinal axis of said bottle is rotated through a horizontal plane during the time said food is being sucked through said nipple; whereby to maintain the inlet of said valve means submerged in said food during said time.

7. A device as defined in claim 6, and further characterized in that said casing comprises a

shell carrying a nipple supporting portion at one end thereof, and a perforated partition at the other end thereof, said portion and said partition providing a valve chamber for said casing and mounting said valve means therebetween.

8. A device as defined in claim 6, and further characterized in that said valve means comprises frame structure means mounted to rotate in said casing simultaneously, one portion thereof being so constructed and arranged as to rotate around a transverse axis, and the other portion thereof being so constructed and arranged to rotate around a horizontal axis.
